UNITED STATES PATENT OFFICE

2,102,412

CHUCKING MACHINE

George O. Gridley, New Britain, Donald H. Montgomery, Hartford, and Earl H. Wheeler, New Britain, Conn., assignors, by mesne assignments, to The New Britain Machine Company, New Britain, Conn., a corporation of Connecticut

Original application July 16, 1931, Serial No. 551,136. Patent No. 2,055,435, dated September 22, 1936. Divided and this application May 29, 1936, Serial No. 82,424. Renewed July 30, 1937

15 Claims. (CL 29—38)

Our invention relates to a chucking machine and this application is a division of our application, Serial No. 551,136, filed July 16, 1931.

It is a general object of the invention to provide a machine of the character indicated, having improved chucking and clutching means interrelated and acting in a manner to make for high speed production, ease of operation, and safety.

10 It is another object to provide in a chucking machine interrelated fluid pressure actuated clutching and chucking means under a single control.

15 It is another object to provide in a machine of the character indicated fluid pressure clutching and chucking means, together with means for assuring a proper sequence of chucking, clutching, unclutching, and unchucking work pieces.

20 Another object is to provide improved fluid pressure actuated chucking and/or clutching mechanism.

Other objects and various features of novelty and improvement will be hereinafter pointed out 25 or will become apparent upon a reading of the specification.

The invention in its preferred form is embodied in a multiple spindle chucking machine, only those parts necessary to an understanding of the 30 invention of this application being shown herein. Other features, such as the frame, driving means, and other general features are disclosed fully in the aforesaid application of which this application is a division and to which reference is hereby 35 made for a fuller disclosure of all features of the machine.

In the drawings which show, for illustrative purposes only, a preferred form of the invention—

40 Fig. 1 is an axial rear end view of a chucking machine, partly broken away and parts shown in section and illustrating features of the invention;

45 Fig. 2 is a sectional view taken substantially in the plane of the line 2—2 of Fig. 1;

Fig. 3 is a sectional view taken substantially in the plane of the line 3—3 of Fig. 1;

50 Fig. 4 is a sectional view taken substantially in the plane of the line 4—4 of Fig. 3;

Fig. 5 is a sectional view taken substantially in the plane of the line 5—5 of Fig. 3;

55 Fig. 6 is a fragmentary top plan view in partial section of clutch and chuck controlling means, also shown in part in Fig. 1;

Fig. 7 is a view in section of parts shown in Fig. 6 but seen from the side, the section being taken substantially in the plane of the line 7—7 of Fig. 1;

5 Fig. 8 is a more or less diagrammatic or illustrative view of our improved fluid pressure actuated chucking and clutching mechanism, together with fluid pressure generator and controls.

10 So much of the drawings of the aforesaid patent application as are necessary for an understanding of the present invention are included herein, but for a fuller description of the entire machine reference is made to the aforesaid application.

15 Each chucking spindle 250 may be supported in the indexible spindle carrier 98 in substantially the same manner and on anti-friction bearings as has been described in connection with the screw machine disclosed in the parent application above identified, and the advantages there noted are, of course, inherent in a chucking machine as well as in the screw machine. In the form shown, and referring particularly to Fig. 2, it will be noted that the main spindle drive gear 183 drives a ring gear 251 rotatably carried on each spindle as by means of a double row bearing 252. The inner ring of the bearing is preferably rigidly carried directly on the spindle 250 while the outer ring is rigidly carried in a recess or bore of the ring gear 251. An advantage of an anti-friction bearing at this point is that when the spindle is unclutched from the drive gear and the drive gear continues to rotate, there is practically no tendency for the spindle to be dragged along with the drive gear, and stopping of the spindle is thus greatly facilitated. We have devised a most advantageous type of clutch device by means of which the spindle is positively driven and yet no difficulty is experienced in engaging the positive clutch regardless of the normal speed of the driving portion thereof. Our improved clutch is disclosed in the present application merely by way of example as a satisfactory clutch for use in the present combination. In the embodiment of the invention herein disclosed, we employ a positive type of bump or toothed clutch for positively driving the spindle during its normal and working rotation, and in order to permit such a desirable and positive type of clutch to be employed at the high speeds at which we desire to employ it, we provide a friction pick-up which initiates the rotation of the spindle and brings it to such a speed, that is, a speed approaching the speed of the driving portion of

the positive clutch, that the positive clutch may be engaged without difficulty.

In the form illustrated, the ring gear 251 or any part which rotates therewith is provided with 5 a driving clutch part 253, having positive clutch teeth 254 thereon. The spindle carries a coacting clutch part, in this case in the form of a sliding sleeve 255, having clutch teeth 256 to engage with the teeth 254. The sleeve 255 is splined at 10 257 to what I term an abutment sleeve 258, which is itself splined at 259 to the spindle 250. The sleeve or spool 255 is provided with a groove 260, so that the sleeve may be actuated by a fork part 261 (Figs. 1, 2), as will be later described. The 15 abutment sleeve 258 is adjustably held in desired longitudinal position on the spindle by means of an adjusting nut device 262, so that it may be moved forwardly or rearwardly for purposes of adjustment, as will be described. Opposite the 20 inner end of the abutment sleeve 258 is a second abutment sleeve or collar 263, which may abut or form part of a friction clutch device 264 formed of plates, one or more of which may be carried by the ring gear, and one or more of which may be 25 carried by the spindle or a part rotatable therewith, so that when the abutment collar 263 is moved toward the right as viewed in Fig. 2, the friction clutch device will be engaged and the spindle will rotate with its driving ring gear 251. 30 In order to cause engagement or disengagement of the friction clutch device we employ wedge members, such as balls 265, which may be carried in pockets or slots in the end of the abutment collar 263. The surfaces on the abutment collar 263 and on the abutment sleeve 258 are inclined to each other, in this case by beveling off the edge of the abutment sleeve 258. Thus, it will be seen that by moving the balls radially inwardly, the tendency will be to separate the abutment members 258—263, and since the abutment member 258 is rigidly held by the adjusting nut 262, the abutment collar 263 will be moved toward the right, to cause the friction clutch 264 to be engaged. The positive clutch sleeve 255 is provided with a 45 bell-mouthing opening 266, so that when the clutch sleeve 255 is in its left-hand position as viewed in Fig. 2, the balls 265 may move radially outwardly to permit disengagement of the friction clutch device 264.

Now, when the sleeve 255 is moved toward the right, the balls 265 will be moved radially inwardly by the tapered or bell-mouthing opening of the clutch sleeve 255, and thus the friction clutch device 264 will be engaged and the spindle 250 will 50 be rotated thereby. Within the sleeve 255 is a cylindrical opening 267 to maintain the balls in their radially inward position. When the spindle 250 has picked up speed, whether it be the same speed as the drive gear 251 or slightly less, the 55 positive clutch sleeve 255 may be moved farther towards the right, so as to cause the enlargement 268 in the clutch sleeve opening or counterbore to be positioned over the balls, and the balls are thus permitted to move radially outwardly and to dis- 60 engage the friction clutch device 264. Further movement of the positive clutch sleeve 255 will cause the positive clutch teeth 254—256 to be engaged with each other, and since the friction clutch device has already initiated the rotative 65 movement of the spindle 250, there will be no difficulty in causing the positive clutch teeth which are now rotating to engage with each other without clashing or grinding of teeth. When it is desired to stop the spindle, the clutch sleeve 70 75 255 is merely moved toward the left, which action

first causes the positive clutch teeth to become disengaged and which incidentally in the form shown causes the friction clutch device to be engaged and immediately thereafter causes the friction clutch means to be disengaged by the radially outward movement of the balls 265 when they enter the tapering or bell-mouthing opening of the sleeve.

Adjustment of the friction clutch pick-up means is readily effected by turning up the adjusting nut 262 so as to bring the two abutment sleeves closer together. Wear in the friction clutch device is thus compensated for. It will be seen that by means of our improved clutch device the spindles may be rotated at exceedingly high rates of speed and by a positive clutch. The friction clutch portion of our device acts only as a spindle speed pick-up device and does not, in the preferred form, drive the spindle at times when work carried by the spindle is being acted upon by the tools. At such times, the spindle is being driven by the positive clutch with all the attendant advantages of such a clutch.

It might be here stated that in the preferred form each spindle clutch is provided with its independent fork device 261 (Fig. 1) which may be slidably mounted upon the studs 227 described in the aforesaid application and employed in the screw machine for supporting the chucking slide. Each fork device 261 is also provided with a finger 30 269 which may be engaged with a track or slide shoe portion 270 (Figs. 1, 6), which is fluid pressure actuated as will be later described. Each fork 261, or, rather, the finger portion 269 thereof of each spindle in other than the chucking position, may be engaged and held against endwise unchucking movement by a track ring 271 on the frame.

The chucks of the chucking machine are fluid pressure actuated. The chucks may be of any 40 desired type, and we have illustrated (Fig. 2) a rather well-known type of two-jaw chuck which is actuated to close the same by a rearward movement of the draw rod and to be opened by a forward movement thereof.

In the preferred form we employ a cylinder and piston for each chuck, and the cylinders are preferably so arranged as to be non-rotatable even though the spindles themselves are rotatable at high speed. A rear portion of each spindle may be provided with an additional anti-friction bearing 273, and at the extreme rear end of the spindle is an anti-friction bearing 274, which supports the non-rotatable cylinder unit 275 of desired form. The cylinder unit 275 is provided with fluid pressure inlet and outlet ports or passages 276—277 at opposite sides of the piston 278. The piston has projecting gudgeons 279—280, which project respectively at the rear and forward ends of the cylinder and which may fit relatively tightly. Stuffing boxes may, if desired, be provided, but, generally speaking, a relatively tight fit will serve to retain the pressure fluid in the cylinder, and if oil, for example, is the pressure fluid, a slight leakage of oil is rather advantageous for lubricating various bearings and parts adjacent to the leaks. Mounted on the piston gudgeon 279 is an anti-friction bearing 281, which supports a frame or yoke device 282, which is rigidly but adjustably secured to the rear end of the draw rod 272, as 50 55 60 65 70 75 80 85 90 95 100 by means of a screw threaded connection and a lock nut 283. It will be seen that, with the cylinder 275 held stationary, the spindle 250 may rotate relatively thereto by reason of the bearing 274. Likewise, the draw rod 272, by reason of the 70 75 80 85 90 95 100

bearing 281, may rotate relatively to the piston. The piston 278 may rotate to some extent in the cylinder, but under normal conditions the principal rotation will be between the draw rod 272 and the piston.

For the purpose of actuating the spindle clutch through the fork device 261 and the shoe or track actuator 270 we employ a fluid pressure piston and cylinder. The track actuator 270 10 may be in the form of a bracket device slidably mounted upon the rods 217 and 218 on the frame of the machine. A piston rod 284 may be adjustably secured to the bracket 270 and be actuated by a fluid pressure piston 285 in a cylinder 15 286, fixed on the frame or rods 217-218, to be described more in detail. The flow of fluid pressure to opposite ends of the cylinder 286 is controlled by a piston valve 287 in a valve casing 288, which piston valve may be manually actuated 20 through its rod 289, link 290 and crank 291 on shaft 292, which may be manually rocked by a handle at any convenient position on the machine.

The fluid pressure connections and the flow of fluid may be traced best by reference to the diagrammatic showing of Fig. 8. In the present embodiment the device is arranged so that all of the chucking cylinders in positions other than the loading position are maintained in chuck-closing position by direct pump pressure, while the cylinder of the spindle in loading position is initially actuated by fluid from an accumulator, the pressure on the actuated piston being thereafter maintained constant by the pump after the accumulator pressure has caused it to operate. In 30 the form shown we employ a pump, such as a gear or other positive type pump, 293, one branch 294 of the discharge side of which communicates with a passage 295 in the accumulator valve housing. A spring pressed valve 296 acts as a pressure regulating valve, to permit the entry of high pressure fluid from the line 294 into the accumulator bell 297. The setting of the valve 296 determines the limit below which the pump discharge pressure may not fall during normal operation. A differential relief valve 298 is provided which is forced to the position indicated in Fig. 8 by the pump pressure fluid. When the accumulator is charged, the pressure of the accumulator fluid shifts the valve 298 to uncover the relief passage 40 299 to discharge excess fluid from the accumulator. When the system is shut down the pump of course ceases to furnish pressure fluid and the spring pressed valve 296 is moved to the extreme left as viewed in Fig. 8 so as to permit 45 the accumulator to drain through the dotted line port of the valve 296 and the drain pipe communicating with the spring chamber of the valve. During normal operation the pump pressure maintains the valve 296 in a right hand position 50 55 to blank off the dotted line port therein.

We may employ a valve 300 urged upwardly by a spring 302. This valve normally closes the discharge from the accumulator, and pump pressure fluid may flow through port 301, beneath the 60 valve skirt, and through ports in skirt to cylinder line 303 to maintain the piston 278 in chucking position in its extreme position. When the chucking lever is actuated to shift the valve 287 as above described, there will be a quick flow of pump fluid through cylinder line 303, port 304, etc., 65 thus momentarily reducing the pump pressure below the valve 300, and the accumulator pressure, being momentarily greater, will shift the valve 300 to cause the skirt of the valve to cut off the port 301 to thus maintain pump pressure on the 70 75

cylinders in working positions (through line 305) and the accumulator will discharge through cylinder line 303 to shift the piston 278 in loading station. When the pressure in the accumulator drops, the spring 302 moves the valve 300 to again 5 close the accumulator discharge to line 303 and again permit direct pump pressure to enter cylinder line 303 to either complete movement of the piston 278 in chucking position, or, if its movement is completed, to maintain the same under 10 static pump pressure. Thus the large volume of accumulator pressure fluid is available for shifting the chucking piston in loading position and direct pump pressure is available for completing the piston shifting and maintaining the same under 15 static pump pressure. An operation may then be performed on a work piece chucked in loading position.

The other branch 305 from the discharge side of the pump communicates with an inlet passage 20 306 in the distributor sleeve 307, which is secured to the frame. Within the sleeve and normally in fixed rotative position is a distributor plug 308, and an annular passage 309 is provided, preferably in the plug itself, so that there is a constant 25 communication between the pump inlet passage 306 and such annular passage. Communicating with the annular passage 309 is a longitudinal passage 310 in the plug which communicates at the forward end of the latter through a side outlet 311 with an interrupted annular groove passage 312 in the plug. The groove 312 extends circumferentially about three-quarters of the way around the plug.

The spindle carrier itself or some part indexible with the chucking cylinders 275 carries a sleeve 313, fitting but indexible with the cylinders about the normally fixed plug 308. The sleeve 313 in the plane of the line 5-5 (Fig. 3) is provided with four outlet passages 314, 315, 316, 40 317, each of which passages is connected, as by means of a pipe 318, 319, 320, 321, respectively, with the tail end of the chucking cylinders 275. Pressure exerted on said tail end serves to draw each draw-rod 272 in the chucking direction. 45 Thus it will be seen that with the plug 308 and sleeve 313 in the position shown in Fig. 5, the tail ends of three of the cylinders will be in communication with the interrupted annular groove 312, and consequently in communication with the 50 longitudinal passage 310, annular groove 309 in the plug, inlet passage 306 in the frame sleeve 307, and the discharge side 305 of the pump. Consequently, the three chucks in the positions other than loading position will be constantly 55 held closed by high pressure fluid directly from the discharge side of the pump.

The distributor sleeve 313 is provided in the plane of the line 4-4 (Fig. 3) with passages 322, 323, 324 and 325, which are in communication, 60 respectively, through pipes 326, 327, 328 and 329 with the head ends of all of the chucking cylinders. The plug 308 is provided in the plane of the line 4-4 of Fig. 3 with an interrupted annular groove 330, with which the passages 323, 65 324, 325 are in open communication, as shown in Fig. 4, so that the head ends of each of the cylinders, other than the one in the loading position, are in open communication with such interrupted annular groove. Communicating with that groove 330 is a longitudinal passage 331, which communicates with an exhaust opening 332 (Figs. 3, 8), for example, with the space between the two sleeves on the plug. Thus, the head end of each of the cylinders, other than the 70 75

one in the loading position, will be in constant communication with the atmosphere, while the tail ends of each of those same cylinders will be in constant communication (Fig. 5) with high pressure fluid directly from the discharge side of the pump.

The plug 308 is provided with a longitudinal passage 333 in constant communication with an annular groove 334 in the plug. Passage 333 is 10 in communication at one end through a plug radial passage 335 (Fig. 5) with the port or passage 317 communicating through the pipe 321 with the tail end of the cylinder in loading position. The plug 308 is provided with another 15 longitudinal passage 336, which communicates with an annular groove 337 in the plug, and at its opposite end communicates through a radial passage 322' (Fig. 4), pipe connection 322 in sleeve 313, and through pipe 326 with the head 20 end of the cylinder in loading position, that is, the upper cylinder in Fig. 8.

The annular plug passage 334 which, as stated, communicates with the tail end of the cylinder in loading position, is connected through 25 pipe connection 338 and pipe 339 with the top pipe connection 340 in the clutch cylinder 286. The annular plug passage 337 which, as stated, is in communication with the head end of the cylinder in loading position, communicates 30 through the pipe connection 341 and pipe 342 with an end passage 343 in the control valve casting 288.

The operation is as follows:

With the parts in substantially the position 35 shown in the drawings, and referring particularly to Figs. 3 to 8, it will be seen that the three chucks in working position are closed and held closed by high pressure fluid directly from the discharge side of the pump. The fluid pressure actuated 40 spindle clutches heretofore described are likewise closed, so that the three spindles in working positions will be rotating with the chucks closed and held closed by direct pump pressure. The spindle in loading position, that is, the upper position 45 in Fig. 8, has the spindle drive clutch thrown out, so that the spindle is stationary, and the chucking piston is in its forward position, so that the chuck is open. The control valve handle has been thrown over to the right to the position indicated as "1st" (Fig. 8).

It may then be seen that the spindle clutch has 50 been thrown out by accumulator pressure fluid which has passed from the accumulator through pipe 303, pipe connection 304, into the annular 55 space between the ends of the spool valve 287, and then through the passage 344 and into the tail end of the cylinder 286, thus maintaining the spindle clutch piston 285 in the left-hand position as viewed in Figs. 7 and 8. At the same time 60 the tail end of the chuck cylinder in loading position will be in communication through the pipe 321, passage 317 (Fig. 5), passages 335 and 333, annular passage 334, pipe connection 338, pipe 339 and pipe connection 340 in the clutch cylinder 286, the annular piston groove 345 in the clutch piston 285, and through the passage 346 in the control valve cylinder, with the exhaust 65 passage 347.

Pressure fluid is free to flow from the space 70 between the pistons of the control valve through port 343, pipe 342, pipe connection 341 and longitudinal plug passage 336, passage 322' (Fig. 4), pipe connection 322 and pipe connection 326 to the head end of the cylinder in loading position, and thus cause the chucking piston of the cylinder 75

in loading position to remain forward and the chuck open.

A new piece of work may now be inserted in the chuck. The manual valve control handle is then shifted to the position indicated "2nd" in Fig. 8, which moves the end 349 of spool valve 287 so as to be positioned under the partition or barrier 350, and the rear piston head 351 between the port 343 and the port 344. In this position pressure fluid entering through pipe 303 and passage 304 is still permitted to pass through passage 344 into the tail end of the clutch control cylinder 286, so as to maintain the spindle clutch in unclutched or open position. At the same time the pipe 342 leading to the control plug 308, and eventually to the head end of the cylinder in loading position, will be opened to the exhaust passage 347, and pressure fluid may pass through pipe 303, pipe connection 304, passage 346, annular passage 345, pipe connection 340 20 and pipe 339, and eventually to the tail end of the cylinder in loading position, so as to close the chuck. The spindle will still be unclutched but the work will now be chucked.

In order to close the spindle clutch the manual control valve handle is thrown toward the left to the position indicated "3rd" in Fig. 8. This movement will place the control valve 287 in the extreme left-hand position. It will be seen that pressure fluid through the pipe 303 and central connection 304 may still pass momentarily through passages 346, 345 to pipe 339, to the tail end of the cylinder in loading position, so as to maintain the work chucked, but at the same time the tail end of the cylinder 286 is in communication through the passage 344 and to the right of the right-hand piston 351 of the control valve with the exhaust passage 347 and the head end space 352 of the clutch cylinder 286 will then be in communication with the source of pressure between the two heads of the piston valve, and the clutch piston 285 will be moved toward the right, so as to throw the spindle clutch in, and the spindle rotation will then be started. After the shift of the clutch piston 285 to the right to 45 close the clutch pressure fluid may still reach the tail end of chucking cylinder in loading position by passing by the head end of cylinder 286 and through pipe 339, etc., to maintain that chuck closed.

After the turret or spindle carrier has indexed, another spindle will then arrive in loading position, and it will be in the same condition that the spindle which just left the loading position was in, that is to say, the spindle will be rotating and the work will be chucked. The manual control valve handle is then shifted to the right, back to the position indicated "2nd". Then, through the pipe connections heretofore described, the tail end of the clutch cylinder 286 will be put in communication with pressure fluid and the head end 352 of that cylinder will be put in communication with the exhaust, so that the clutch piston 285 will be shifted toward the left and will again occupy the position shown in Figs. 7 and 8, and the spindle clutch will be thrown out but the work will still be clutched. The manual control valve handle would then be shifted farther toward the right, to the position designated "1st", which is the position in which the parts are in Figs. 7 and 8. This further shifting of the control valve to its extreme right hand position will still permit pressure fluid to maintain the clutch piston 285 in its left hand position, so as to maintain the clutch open, but 75

through the pipe connections heretofore described the tail end of the cylinder in chucking position will be opened to the atmosphere, and the head end will be opened to accumulator pressure, to open the chuck, so as to discharge the finished work piece and permit the insertion of a new work piece.

Thus briefly, with the parts in the position shown in Figs. 7 and 8, the first shift of the manual control handle to the "2nd" or intermediate position will cause work to be chucked. Further movement of the handle to the extreme left or "3rd" position will cause the spindle to be clutched, and thereafter the spindle carrier indexes. Another spindle then reaches the loading position. Movement of the manual control handle toward the right to the "2nd" position will cause the spindle to be unclutched, and further movement of the control valve handle back to the extreme right, or "1st" position, as shown in the drawings, will cause the work to be unchucked. Thus the cycle is completed.

It is often desirable in a machine of this character to permit a chuck in any position to be opened, for example so that a faulty piece of work may be removed. With that end in view we have provided means for rotating the distributor plug 308 from its normal position, as shown in the drawings, so as to place the various passages heretofore described into communication with the various cylinders. For example, it will be clear that with the holding or detent lug device 353 withdrawn to the position shown in Fig. 3, the handle 354 may be moved so as to rotate the distributor plug 308 to any position desired, so as to cause the passages now in communication with a particular cylinder to be placed in communication with any of the other cylinders. In fact, if it were desired, the loading position of the machine could be almost instantly changed merely by shifting the distributor plug 308 to the appropriate position.

While we have disclosed many features of novelty having structural or functional utility, it is to be noted that we have disclosed only a preferred form and that many changes, modifications, additions, and omissions may be made within the scope of the invention as defined in the appended claims.

50 We claim:

1. In a chucking machine, a rotatable spindle, a chuck carried thereby, a fluid pressure actuated means for actuating said chuck, means for driving said spindle, a clutch controlling the same, a fluid pressure actuated means for actuating said clutch, and a single valve for controlling the flow of pressure fluid for both said fluid pressure actuated means.

2. In a chucking machine, a frame, a rotatable spindle, a chuck carried thereby, fluid pressure actuated means for actuating said chuck, means for driving said spindle, a clutch controlling the same, a fluid pressure actuated means carried by said frame and positioned for coaction with said clutch, and a single valve for controlling both of said fluid pressure actuated means.

3. In a chucking machine, a rotatable spindle, a chuck carried thereby, fluid pressure actuated means for actuating said chuck, means for driving said spindle, a clutch for controlling said driving means, fluid pressure actuated means for actuating said clutch, means for conducting pressure fluid to both said fluid pressure actuated means, and a single valve movable to one position to control the flow of fluid pressure for said

clutch actuating means and movable to another position to control said chuck fluid pressure actuated means.

4. In a chucking machine, a rotatable spindle, a chuck carried thereby, fluid pressure actuated means for actuating said chuck, means for driving said spindle, a clutch for controlling the same, fluid pressure actuated means for actuating said clutch, and means controlled from a single point for controlling the flow of pressure fluid to said clutch actuating means for disengaging said clutch and for thereafter controlling the flow of pressure fluid to said chuck actuating means for opening said chuck.

5. In a chucking machine, a frame, a rotatable spindle, a chuck carried thereby, fluid pressure means for actuating said chuck, means for driving said spindle, a clutch for controlling the same, a fluid pressure cylinder carried by said frame, a piston therein, means forming a coacting means between said piston and clutch for actuating the latter by said piston, and fluid passage means through said cylinder and leading to said fluid pressure actuated means for said chuck for actuating the latter.

6. In a chucking machine, a rotatable spindle, a chuck carried thereby, fluid pressure actuated means for actuating said chuck, means for driving said spindle, a clutch for controlling the same, fluid pressure actuated means for actuating said clutch, and a single control means for first controlling the flow of fluid to one of said fluid pressure actuated means to actuate the same, and thereafter controlling the flow of pressure fluid to the other of said fluid pressure actuated means for actuating the latter.

7. In a chucking machine, a rotatable spindle, a chuck carried thereby, fluid pressure actuated means for actuating said chuck, means for driving said spindle, a clutch for controlling the same, fluid pressure actuated means for actuating said clutch, and control means movable to one position for controlling the flow of fluid pressure to one of said fluid pressure actuated means and movable to another position for controlling the flow of fluid pressure to the other of said fluid pressure actuated means, for the purpose described.

8. In a chucking machine, a spindle carrier, means for indexing the same from station to station, a plurality of rotatable spindles carried by said spindle carrier, means for driving said spindles, clutch means for connecting said driving means to each of said spindles, a chuck carried by each of said spindles, fluid pressure actuated means for actuating the chuck of each of said spindles in loading station, and a single control valve for controlling the flow of pressure fluid to each of said fluid pressure actuated means.

9. In a chucking machine, a frame, an indexable spindle carrier carried thereby, a plurality of rotatable spindles carried by said spindle carrier, means for indexing said spindle carrier, a chuck carried by each of said spindles, fluid pressure actuated chucking means carried by each of said spindles for actuating the chucks thereof, means for driving said spindles, a spindle clutch for clutching and unclutching each spindle from said driving means, fluid pressure actuated means carried by said frame and coacting with each clutch when in loading station, and means controlled from a single point for controlling both said fluid pressure actuated means for first unclutching a spindle and thereafter opening the chuck of such spindle.

10. In a chucking machine, a frame, an in-

- 6 flexible spindle carrier thereon, a plurality of rotatable spindles carried by said spindle carrier, means for indexing said spindle carrier, a chuck carried by each said spindle, means for driving said spindles, means for disengaging each said spindle from its driving means including a fluid pressure actuated means, a fluid pressure actuated means for actuating each of said chucks in loading station, and a single control valve for controlling the flow of pressure fluid to each of said fluid pressure actuated means, for the purpose described.
11. In a chucking machine, a frame, an indexable spindle carrier thereon, a plurality of rotatable spindles carried by said spindle carrier, means for driving said spindles, fluid pressure actuated means for disengaging each of said spindles from said driving means, a chuck carried by each spindle, fluid pressure actuated means for actuating said chucks, and a single valve movable to one position to control the flow of fluid pressure to said spindle drive disengaging means and movable to another position to control the flow of pressure fluid to said chuck fluid pressure actuated means, for the purpose described.
12. In a chucking machine, a frame, an indexable spindle carrier, a plurality of rotatable spindles carried thereby, a chuck carried by each said spindle, spindle driving means, spindle drive disengaging means, a fluid pressure actuated piston for actuating said spindle drive disengaging means, a fluid pressure operated piston for actuating the chuck of each said spindle when in loading station, and a single fluid pressure control means for controlling the flow of fluid pressure to said two fluid pressure means.
13. In a machine of the character indicated, a frame, an indexable spindle carrier thereon, a plurality of rotatable spindles carried by said
- 5 spindle carrier, a chuck carried by each said spindle, driving means for said spindles, means for disengaging each of said spindles from its driving means including a slide mounted on said frame, a fluid pressure piston and cylinder for moving said slide for engaging and disengaging said driving means with at least one of said spindles, fluid pressure actuated means for actuating said chucks, fluid passage means including said cylinder for conducting pressure fluid to said chuck fluid pressure actuating means, and valve means for controlling the flow of fluid pressure for said fluid pressure actuated means and said piston and cylinder.
- 10 14. In a chucking machine, a rotatable spindle, a chuck carried thereby, fluid pressure actuated means carried by said spindle for actuating said chuck, means for driving said spindle, means for disengaging said spindle from its driving means including a fluid pressure actuated means, and a single control means movable to one position for controlling the flow of fluid pressure for disengaging said spindle from its drive means and movable to another position to open said chuck while said spindle is disengaged and movable to another position to cause said chuck to close and movable to another position to cause said spindle to again engage with its drive means.
15. In a chucking machine, a rotatable spindle, a chuck carried thereby, a fluid pressure cylinder and piston for actuating said chuck, said cylinder being normally rotatable relatively to said spindle and being rotatably carried by the rear end thereof, valve means for controlling the flow of pressure fluid to and from said cylinder, and means for starting and stopping rotation of said spindle.
